UNITED STATES PATENT OFFICE

JACKSON R. CRONISTER, OF JEANNETTE, PENNSYLVANIA

PROPELLER

Application filed March 12, 1930. Serial No. 435,256.

This invention relates to propellers. One important object of the invention is to provide an improved general construction of propellers.

5 A second important object of the invention is to provide a propeller having improved thrust.

10 A third important object of the invention is to provide a novel propeller having great strength and compactness.

15 A fourth important object of the invention is to provide an improved form of propeller having proper balance at all speeds.

A fifth important object of the invention 20 is to provide an improved form of propeller having a novel hub arrangement.

With the above and other objects in view, the invention consists in general of certain novel details of construction and combinations of parts hereinafter more fully described, illustrated in the accompanying drawings and claimed.

25 In the accompanying drawings, like characters of reference indicate corresponding parts in the several views, and:

Figure 1 is a rear view of the invention;

Figure 2 is a side view thereof;

Figure 3 is a section on the line 3—3 of Figure 1;

30 Figure 4 is a rear elevation of a modified form of the invention;

Figure 5 is a section on the line 5—5 of Figure 6; and

35 Figure 6 is a section on the line 6—6 of Figure 4.

The propeller forming this invention is a two bladed propeller, each blade of which has a leading edge 10 slightly convex in front elevation in the direction of attack and 40 a trailing edge 11 slightly concave in said direction of attack, the propeller being designed to rotate in the direction of the arrow A in Figure 1. Both leading edges lie in a plane at right angles to the axis of rotation 45 of the propeller and the trailing edges lie in a second plane spaced rearwardly of the leading edge plane. Each trailing edge is substantially at right angles to the respective leading edge so that the two planes above mentioned are spaced a distance equal ap-

proximately to one-fourth the pitch of the propeller. The leading and trailing edges of each blade are connected by helical surfaces 12 terminating outwardly in a convex edge 13 reversely curved at its ends to flare into 55 the leading and trailing edges.

In the form of the invention shown in Figures 1, 2 and 3, there is provided a hub 14 of cylindrical shape into which the helical surfaces of the blade merge by gentle curves. 60

Similarly, the form shown in Figures 4, 5 and 6 is provided with a hub 15 of conical form, this being the preferred form of the invention, and the helical blade surfaces merge into this hub by proper curves so as to prevent the setting up of eddy currents causing loss of propulsive power. Moreover, this conical form, by forcing the air outwardly as the propeller is rotated, causes increased air density at the rear inner parts of the propeller and prevents cavitation and losses caused thereby. The merging of the helical and conical surfaces is effected by curved connecting surfaces tangent to the conical and helical surfaces as can best be seen in Figure 5. 75

There has thus been provided a simple and efficient device of the kind described and for the purpose specified.

It is obvious that changes may be made in the form and construction of the invention 80 without departing from the principles thereof. It is not, therefore, desired to confine the invention to the exact form herein shown and described but it is desired to include all such as come within the scope claimed. 85

Having thus described the invention, what is claimed is:

1. A propeller having a hub and a pair of oppositely disposed blades having leading and trailing edges, the trailing edges of said blades being positioned in a plane at right angles to the axis of rotation of the propeller, and the leading edges of the blades being positioned in a second plane at right angles to said axis and spaced along said axis rearwardly of the first plane, each leading edge being spaced substantially ninety degrees about the axis of the propeller from the corresponding trailing edges and the planes in which the leading and trailing edges lie being 100

spaced approximately one-fourth of the pitch distance of the propeller.

2. A propeller having a hub and a pair of oppositely disposed blades having leading and trailing edges, the trailing edges of said blades being positioned in a plane at right angles to the axis of rotation of the propeller, and the leading edges of the blades being positioned in a second plane at right angles to said axis and spaced along said axis rearwardly of the first plane, said leading edges being convex in the direction of attack and the trailing edges being concave in said direction, each leading edge being spaced substantially ninety degrees about the axis of the propeller from the corresponding trailing edges and the planes in which the leading and trailing edges lie being spaced one-fourth of the pitch distance of the propeller.

20 3. A propeller having a hub and a pair of oppositely disposed blades having leading and trailing edges, the trailing edges of said blades being positioned in a plane at right angles to the axis of rotation of the propeller,
25 and the leading edges of the blades being positioned in a second plane at right angles to said axis and spaced along said axis rearwardly of the first plane, each leading edge being connected to the corresponding trailing edge by helical surfaces terminating outwardly in a concave edge, each leading edge being spaced substantially ninety degrees about the axis of the propeller from the corresponding trailing edges and the planes in
30 which the leading and trailing edges lie being spaced approximately one-fourth of the pitch distance of the propeller.
35

4. A propeller having a hub and a pair of oppositely disposed blades having leading and trailing edges, the trailing edges of said blades being positioned in a plane at right angles to the axis of rotation of the propeller, and the leading edges of the blades being positioned in a second plane at right angles to said axis and spaced along said axis rearwardly of the first plane, said leading edges being convex in the direction of attack, and the trailing edges being concave in said direction, each leading edge being connected to the corresponding trailing edge by helical surfaces terminating outwardly in a concave edge, each leading edge being spaced substantially ninety degrees about the axis of the propeller from the corresponding trailing edges and the planes in which the leading and trailing edges lie being spaced approximately one-fourth of the pitch distance of the propeller.

5. A propeller having a hub and a pair of oppositely disposed blades having leading and trailing edges, the trailing edges of said blades being positioned in a plane at right angles to the axis of rotation of the propeller and the leading edges of the blades being positioned in a second plane at right

angles to said axis and spaced along said axis rearwardly of the first plane, said hub being of conical form with its apex forward and having the helical surfaces merging into the surface of the cone along curved surfaces tangent to the conical and helical surfaces. 70

6. A propeller having a hub and a pair of oppositely disposed blades having leading and trailing edges, the trailing edges of said blades being positioned in a plane at right angles to the axis of rotation of the propeller, and the leading edges of the blades being positioned in a second plane at right angles to said axis and spaced along said axis rearwardly of the first plane, said leading edges being convex in the direction of attack and the trailing edges being concave in said direction, said hub being of conical form with its apex forward and having the helical surfaces merging into the surface of the cone along curved surfaces tangent to the conical and helical surfaces.

7. A propeller having a hub and a pair of oppositely disposed blades having leading and trailing edges, the trailing edges of said blades being positioned in a plane at right angles to the axis of rotation of the propeller, and the leading edges of the blades being positioned in a second plane at right angles to said axis and spaced along said axis rearwardly of the first plane, each leading edge being connected to the corresponding trailing edge by helical surfaces terminating outwardly in a concave edge, said hub being of conical form with its apex forward and having the helical surfaces merging into the surface of the cone along curved surfaces tangent to the conical and helical surfaces.

8. A propeller having a hub and a pair of oppositely disposed blades having leading and trailing edges, the trailing edges of said blades being positioned in a plane at right angles to the axis of rotation of the propeller, and the leading edges of the blades being positioned in a second plane at right angles to said axis and spaced along said axis rearwardly of the first plane, said leading edges being convex in the direction of attack, and the trailing edges being concave in said direction, each leading edge being connected to the corresponding trailing edge by helical surfaces terminating outwardly in a concave edge, said hub being of conical form with its apex forward and having the helical surfaces merging into the surface of the cone along curved surfaces tangent to the conical and helical surfaces. 103 110 111 112

9. A propeller having a hub and a pair of oppositely disposed blades having leading and trailing edges, the trailing edges of said blades being positioned in a plane at right angles to the axis of rotation of the propeller, and the leading edges of the blades being positioned in a second plane at right angles to said axis and spaced along said axis rear-

- wardly of the first plane, each leading edge being spaced substantially ninety degrees about the axis of the propeller from the corresponding trailing edges and the planes in
 5 which the leading and trailing edges lie being spaced approximately one-fourth of the pitch distance of the propeller, said hub being of conical form with its apex forward and having the helical surfaces merging into the surface of the cone along curved surfaces tangent to the conical and helical surfaces.
10. A propeller having a hub and a pair of oppositely disposed blades having leading and trailing edges, the trailing edges of said blades being positioned in a plane at right angles to the axis of rotation of the propeller, and the leading edges of the blades being positioned in a second plane at right angles to said axis and spaced along said axis
 15 rearwardly of the first plane, said leading edges being convex in the direction of attack and the trailing edges being concave in said direction, each leading edge being spaced substantially ninety degrees about the axis of
 20 the propeller from the corresponding trailing edges and the planes in which the leading and trailing edges lie being spaced one-fourth of the pitch distance of the propeller, said hub being of conical form with its apex
 25 forward and having the helical surfaces merging into the surface of the cone along curved surfaces tangent to the conical and helical surfaces.
11. A propeller having a hub and a pair of oppositely disposed blades having leading and trailing edges, the trailing edges of said blades being positioned in a plane at right angles to the axis of rotation of the propeller, and the leading edges of the blades being positioned in a second plane at right angles to said axis and spaced along said axis rearwardly of the first plane, each leading edge being connected to the corresponding trailing edge by helical surfaces terminating outwardly in a concave edge, each leading edge being spaced substantially ninety degrees about the axis of the propeller from the corresponding trailing edges and the planes in which the leading and trailing edges lie being spaced approximately one-fourth of the pitch distance of the propeller, said hub being of conical form with its apex forward and having the helical surfaces merging into the surface of the cone along curved surfaces tangent to the conical and helical surfaces.
- In testimony whereof I affix my signature.
 JACKSON R. CRONISTER.
12. A propeller having a hub and a pair of oppositely disposed blades having leading and trailing edges, the trailing edges of said blades being positioned in a plane at right angles to the axis of rotation of the propeller, and the leading edges of the blades being positioned in a second plane at right angles to said axis and spaced along said axis rearwardly of the first plane, each leading edge being convex in the direction of attack, and
